[57] CLAIM

The ornamental design for a bottle body with beveled end, as shown and described.

DESCRIPTION

FIG. 1 is a perspective view of a first embodiment of a bottle body constructed in accordance with our new design;
FIG. 2 is a top plan view of the first embodiment;
FIG. 3 is a front elevational view of the first embodiment;
FIG. 4 is a right side elevation of the first embodiment, the left side elevation is a mirror image thereto;
FIG. 5 is a rear elevational view of the first embodiment;
FIG. 6 is a bottom plan view of the first embodiment;
FIG. 7 is a front elevational view of a second embodiment of a bottle body with beveled end constructed in accordance with our new design;
FIG. 8 is a right side elevation of the second embodiment, the left side elevation is a mirror image thereto;
FIG. 9 is a perspective view of the second embodiment;
FIG. 10 is a top plan view of the second embodiment;
FIG. 11 is a rear elevational view of the second embodiment; and,
FIG. 12 is a bottom plan view of the second embodiment. The broken lines in the drawings are for illustrative purposes only and do not form part of the claimed design.
